CLAIM

The ornamental design for a chair seat, as shown and described.

DESCRIPTION

FIG. 1 is a front perspective view of a chair seat, showing our new design;

FIG. 2 is a rear perspective view thereof;

FIG. 3 is a side elevational view, the opposite side being a mirror image thereof;

FIG. 4 is a front elevational view thereof;

FIG. 5 is a rear elevational view thereof;

FIG. 6 is a top plan view thereof;

FIG. 7 is a front perspective view of a chair seat, showing a second embodiment of our new design;

FIG. 8 is a rear perspective view thereof;

FIG. 9 is a side elevational view, the opposite side being a mirror image thereof;

FIG. 10 is a front elevational view thereof;

FIG. 11 is a rear elevational view thereof;

FIG. 12 is a top plan view thereof; and,

FIG. 13 is a bottom plan view thereof.
